WALTER E. LIPPERT, OF HEWLETT, NEW YORK, ASSIGNOR TO SAMUEL BONAT AND HARRY BONAT, DOING BUSINESS AS SAMUEL BONAT & BRO., OF NEW YORK, N. Y.

METHOD AND APPARATUS FOR WAVING HAIR

Application filed August 14, 1931. Serial No. 556,995.

This invention relates to the waving of hair to produce so-called "permanent waves" in living hair on the human head.

Various methods of waving hair are now 5 in use, including the "spindle method" in which separate strands of hair are wound on spindles. The hair after winding is moistened with a suitable treating solution, usually wrapped with a strip of cloth and/or 10 paper, and then subjected to heat until the wave is fixed.

It is customary to wind each strand in the same direction upon its spindle. When the heating is completed and the spindles are 15 moved, the hair is washed and then subjected to further operations including "finger waving" to give the hair the desired appearance. When the hair is so treated the strands have a tendency to separate, and it 20 is difficult to secure a natural appearance and an otherwise satisfactory wave, even after prolonged manipulation.

I have discovered that the difficulties encountered in securing satisfactory waves in 25 the hair can be overcome by winding the separate and contiguous strands of hair in reverse directions on the spindles. When the hair is thus treated and the spindles are removed after the heat has been applied, the 30 strands tend to fall naturally into the desired positions and a more desirable appearance is secured with a minimum of manipulation.

It is the object of the present invention to provide a simple and effective method and 35 apparatus whereby the waving of hair is facilitated and improved results are secured, and I have devised a method and apparatus whereby these objects are accomplished as set forth in the following specification.

40 In carrying out the invention, I divide the hair on the head into groups in accordance with the usual practice and then separate each group into two strands automatically by the application of a clamp which is disposed adjacent to the scalp and is adapted 45 to firmly hold the strands of hair near the roots thereof. A number of clamps, each firmly gripping two strands of hair, may be distributed over the head, so that all of the 50 strands can be subjected simultaneously to

the waving operation. Each clamp embracing two strands of hair carries two spindles which are secured to the clamp and include rotatable sleeves. The sleeves are adapted to be held from rotation during the winding 55 operation, but are released thereafter to facilitate removal of the hair. Upon each of the sleeves a rotatable winder is mounted, the winder having a helical slot and a projecting finger which is adapted to engage the strand of hair. When the winder is rotated by the application of a key, the hair is wound helically upon the sleeve and is held by the winder during the further procedure 60 of the winding operation. An essential part 65 of the invention is the provision of winders which are adapted to wind the contiguous strands of hair in reverse directions upon the adjacent spindles. The slots and fingers on the winders are so formed that they will 70 only wind the hair on the spindles in the manner indicated.

When the winding of all of the strands is completed, each strand is moistened with a suitable treating agent such for example as 75 a solution containing borax and/or other softening agents and a suitable wrapper is applied. The wrapper may be a strip of flannel which has been moistened in the treating solution, and an outer wrapper of paper, 80 parchment or metal foil can then be applied. The wrapper may be secured by any suitable means. The heaters, each comprising preferably two heating elements surrounding tubular passages, can be placed over the spindles with the strands of hair and wrappers thereon. Heat is applied by supplying current to the heating elements and the heating continues for a sufficient time to fix the wave 85 in the hair. Either open or closed heaters 90 may be employed. Closed heaters retain the steam resulting from the heating within the passages surrounding the wound strands of hair. If open heaters are employed, it is desirable to use impervious wrappers such as 95 metal foil with the ends securely closed to retain the steam during the heating operation. To facilitate the application of the wrappers, I may use metal housings, each comprising two semi-cylindrical members hingedly 100

connected. The moistened wrappers may be placed in these housings which may be closed then upon the wound strands of hair. Springs may be employed in the housings to ensure close contact of the wrappers with the wound strands.

In rewaving, that is to say waving a portion of the hair adjacent the roots without affecting previously waved portions, the procedure is the same except that only the straight hair adjacent the roots is wound upon the spindles. I employ, however, a different type of heater comprising preferably semi-cylindrical members hingedly connected, thus permitting the free ends of the hair to project from the side of the heater so that these ends are not affected by the moisture and heat applied to the straight portions of the hair.

My invention includes numerous improvements involving the method as described and the apparatus illustrated in the accompanying drawings, and particularly details of the clamp with the spindles and winding mechanism supported thereon. Such details will be described with reference to the drawings, in which:

Fig. 1 is an elevation of a clamp with winding spindles supported thereon;

Fig. 2 is a section on the line 2—2 of Fig. 1;

Fig. 3 is a section on the line 3—3 of Fig. 2;

Fig. 4 is a detail in section of a key which is employed to operate the winders and to clamp the sleeves of the spindles;

Fig. 5 is a longitudinal section through the clamp, spindle and winder;

Fig. 6 is a sectional view of the device with the heater arranged to co-operate with the spindles;

Fig. 7 is a sectional view of another form of the heater;

Fig. 8 is an elevation of another form of heater adapted for use in rewaving and illustrating the application thereof to one of the spindles;

Figs. 9 and 10 are sectional views of the heater illustrated in Fig. 8;

Fig. 11 is an elevation of a housing adapted to enclose the strand of hair wound on the spindle;

Fig. 12 is a section on the line 12—12 of Fig. 9;

Figs. 13 and 14 are sections of a slightly different form of housing;

Fig. 15 is a plan view, partially in section, of another form of clamp;

Fig. 16 is a section on the line 16—16 of Fig. 15; and

Fig. 17 is a plan view, partially in section, of a modified form of the clamp shown in Fig. 15.

Referring to the drawings, 5 indicates a clamp comprising opposed elements 6 and 7 hingedly connected at 8. Each of the ele-

ments consists of spaced plates as illustrated, and a locking bar 9 is pivotally connected at 10 to one of the elements and carries a pivoted cam 11 at its other end which is adapted to engage the other element and thus hold the elements firmly in locked position.

A jaw 12 with a projection 13 centrally located and lateral recesses 14 is resiliently supported in one of the clamp elements by springs 15 and is adapted to enter the space between the plates of the other element. When the clamp is applied to the hair the latter is divided automatically into two strands in the recesses 14 and is firmly gripped by the jaw against the opposed faces of recesses 16 in the opposite element of the clamp. The strands of hair are held firmly and a minimum space is afforded through which steam can escape toward the scalp. Preferably a suitable insulating pad, for example a strip of felt 17, is secured to the lower face of the clamp to protect the scalp from heat.

The clamp carries two spindles 18 firmly secured thereto in spaced relation, and a sleeve 19 is loosely supported on each spindle. The sleeves are held against rotation by nuts 20 mounted on the threaded ends of the spindle. The nuts may be tightened by means of a key 21 having a squared opening 22 at one end thereof.

Upon each of the sleeves a winder 23 is mounted. The winder has preferably a split end 24 which is adapted to grip the sleeve frictionally so that the winder will remain fixed in any position on the sleeve. The winder is provided with a helical slot 25 and a projecting finger 26. When the hair is to be wound on the spindle it is first gripped adjacent the roots by means of the clamp and the end is introduced beneath the finger 26 in the slot 25. The winder is then rotated by engagement of ratchet teeth 27 on the key 21 with similar teeth 28 on the end of the winder. As the winder turns the strand of hair is wound helically upon the spindle and the end of the hair is held by the winder so that the strand remains firmly secured in its wound position.

As hereinbefore stated and as indicated in the drawings, the fingers and slots in the winders on the contiguous spindles are directed oppositely so that the adjacent strands of hair must be wound in opposite directions, that is to say, one strand assumes the position of a left-handed helix whereas the adjacent strand assumes the position of a right-handed helix. With the apparatus as described, the adjacent strands cannot be otherwise wound on the spindles.

When all of the strands have been wound as indicated, each strand is moistened with a suitable treating liquid, for example a solution of borax and/or other softening agents, and a wrapper 29, preferably a moistened

strip of flannel, is wound upon each of the strands. The strands may be enclosed also in wrappings 30 of impervious material such as paper, parchment or metal foil, the ends of 5 which may be secured by twisting, tying or other means.

I then apply to each pair of spindles a heater comprising spaced tubes 31, each of which is wound with a heating element 32 10 and suitable insulation 33 and enclosed in a casing 34 with an insulating handle 35. Suitable conductors 36 are connected to the heating elements to supply the current necessary to heat the hair. When the heating is 15 completed, the heater and wrappers are removed and the nuts 20 are loosened so that the sleeves will rotate. The clamp is unlocked and the hair may be withdrawn easily from the spindles, the rotation of the sleeves 20 facilitating this operation. The heater as described is of the open type, that is to say the upper ends of the passages are open, and steam can escape. Wrappers of moisture impervious material are desirable with this type 25 of heater.

In Fig. 7, I have illustrated a closed heater similar to the one previously described, comprising tubes 37 with surrounding heating elements 38 and insulation 39, and a casing 30 40. The upper ends of the tubes are closed by a head 41. Conductors 42 are connected to the heating elements to supply the necessary current.

In Figs. 8 and 9, I have illustrated another 35 type of heater comprising two semi-cylindrical members 48 connected by a spring 49 or by any other suitable resilient hinge connection and provided with insulating handles 50. Each of the semi-cylindrical members 40 includes a casing 53 and a heating element 51 which is supplied with current by conductors 52. With this type of heater only portions 45 of the hair adjacent the roots need be wound on the spindles, the previously waved portions being free. After the wound portions 50 of the hair have been moistened and wrapped, the heaters are applied with the free portions of the hair projecting laterally between the two sections of each heating element so that these portions are not subjected to the moist heat and the previous waving is not disturbed.

To facilitate the operation of applying the 55 wrappers, I may employ hinged housings 43 of light sheet metal, for example, hingedly connected at 44 and provided with openings 45 and a latching means 46. In using such a device, a strip of flannel suitably moistened 60 is placed in one-half of the housing which is then disposed about the wound strand of hair, and the housing is closed, thus bringing the flannel into contact with the moistened hair.

I may employ springs 47 as indicated in Figs. 65 13 and 14, to ensure contact of the moistened

flannel or other wrapping material with the hair.

In Figs. 15 and 16 of the drawings, I have illustrated a slightly different form of clamp 70 designed to permit the removal of the 75 spindles.

The clamp is similar to the device illustrated in Figs. 1 and 2. It comprises opposed elements 56 and 57 hingedly connected at 58. Each of the elements consists of spaced plates 75 as illustrated, and a locking bar 59 is pivotally connected at 60 to one of the elements and carries a pivoted cam 61 at its other end, which is adapted to engage the other element and thus hold the elements firmly in locked position. A jaw 62 with a projection 63 centrally located and lateral recesses 64 is resiliently supported in one of the clamp elements by springs 65 and is adapted to enter the space between the plates of the other element. When the clamp is applied to the hair, the latter is divided automatically into two strands in the recesses 64 and is firmly gripped by the jaw against the opposed faces 80 of recesses 66 in the opposite element of the 85 clamp. The strands of hair are thus held firmly and a minimum space is afforded through which steam can escape toward the scalp. Preferably a suitable insulating pad, 90 for example a strip of felt 67, is secured to the lower face of the clamp to protect the scalp 95 from heat.

To support the spindles 68 I provide openings 69 preferably of different shape in the upper plate of the element 57 to receive reduced extensions of similar shape on the ends of the spindles 68. To lock the spindles, a jaw 70 is slidably supported between the opposed plates of the element 57 and is provided 100 with corresponding openings to receive the extensions on the spindles 68. A cam 71 is pivoted on an extension 72 of the jaw and is provided with a handle 73. The cam is adapted to bear against the plates of the element 57 and when moved to the position indicated in the drawings firmly clamps the extensions of the spindles 68. The latter may be provided with notches, if desired, to prevent removal of the spindles even by the application 105 of force. The spindles can be released 110 readily by moving the cam, as will be readily understood.

In Fig. 17, I have illustrated a slight modification of the device as shown in Figs. 15 and 16, the parts being identical and bearing 120 similar reference characters in the drawings except for the substitution of a clamping nut 74 on a threaded extension of the jaw 75. The nut replaces the cam and bears against 125 the spaced plates of the element 57 so that the jaw firmly grips the extensions on the spindles 68. The spindles may be released readily by loosening the nut.

As mentioned above, the ends of the individual spindles 68 and the openings 69 in 130

the element 57, into which the spindles are adapted to be inserted, are of different cross-sectional shape, as shown in Figs. 15, 16 and 17, so that the spindles 68 cannot be interchanged. This prevents the use of spindles other than those having winders 23 for winding the hair in reverse directions, so that the device is fool-proof and can only be operated in the proper manner.

10 The method and apparatus as described affords numerous advantages, and it particularly facilitates the production of satisfactory waves in the hair by ensuring that contiguous strands are wound in reverse directions on the spindles so that the waves, when formed, will fall naturally into their desired positions to produce an improved and more satisfactory effect.

15 Various changes may be made in the details of the procedure and in the apparatus employed without departing from the invention or sacrificing any of the advantages thereof.

I claim:

20 1. The method of waving living hair which comprises separating the hair into strands, clamping the strands near the roots thereof, winding contiguous strands helically in opposite directions, moistening the hair with a treating solution, and subjecting the hair to heat for a period sufficient to fix the wave therein.

25 2. The method of waving living hair which comprises separating the hair into strands, clamping the strands near the roots thereof, winding portions of contiguous strands adjacent the scalp helically in opposite directions, moistening the hair with a treating solution, and subjecting the hair to heat for a period sufficient to fix the wave therein.

30 3. The method of waving living hair which comprises separating the hair into strands, clamping the strands near the roots thereof, winding contiguous strands helically in opposite directions, moistening the hair with a treating solution, enclosing the hair in wrappers, and subjecting the hair to heat for a period sufficient to fix the wave therein.

35 4. The method of waving living hair which comprises separating the hair into strands, clamping the strands near the roots thereof, winding portions of contiguous strands adjacent the scalp helically in opposite directions, moistening the hair with a treating solution, enclosing the wound portions of the hair in wrappers, and subjecting the hair to heat for a period sufficient to fix the wave therein.

40 5. In an apparatus for waving hair, a clamp, a pair of spindles supported thereon, and means on the spindles to wind the hair helically thereon in reverse directions.

45 6. In an apparatus for waving hair, a clamp, a pair of spindles supported thereon

including sleeves adapted to be rotated when released, means for securing the sleeves against rotation, and means on the spindles to wind the hair helically thereon in reverse directions.

7. In an apparatus for waving hair, a clamp, a pair of spindles supported thereon, and means on the spindles to wind the hair helically thereon in reverse directions, including members loosely mounted on the spindles having helical slots and projecting fingers to engage the hair.

8. In an apparatus for waving hair, a clamp, a pair of spindles supported thereon, and means on the spindles to wind the hair helically thereon in reverse directions, including members loosely mounted on the spindles having helical slots and projecting fingers to engage the hair, and means for rotating the last mentioned members.

9. In an apparatus for waving hair, a clamp, a pair of spindles supported thereon including sleeves adapted to be rotated when released, means for securing the sleeves against rotation, and means on the spindles to wind the hair helically thereon in reverse directions, including members loosely mounted on the spindles having helical slots and projecting fingers to engage the hair.

10. In an apparatus for waving hair, a clamp comprising opposed elements hingedly connected, means for securing the clamp in closed position, a pair of spindles supported on the clamp, and means on the spindles to wind the hair helically thereon in reverse directions.

11. In an apparatus for waving hair, a clamp comprising opposed elements hingedly connected, means for securing the clamp in closed position, a pair of spindles supported on the clamp including sleeves adapted to be rotated when released, and means for securing the sleeves against rotation.

12. In an apparatus for waving hair, a clamp comprising opposed elements hingedly connected, means for securing the clamp in closed position, a pair of spindles supported on the clamp including sleeves adapted to be rotated when released, means for securing the sleeves against rotation, and means on the spindles to wind the hair helically thereon in reverse directions.

13. In an apparatus for waving hair, a clamp comprising opposed elements hingedly connected, means for securing the clamp in closed position, a pair of spindles supported on the clamp including sleeves adapted to be rotated when released, means for securing the sleeves against rotation, and means on the spindles to wind the hair helically thereon in reverse directions, including members loosely mounted on the spindles having helical slots and projecting fingers to engage the hair.

15. In an apparatus for waving hair, a clamp, a pair of spindles mounted thereon, means for winding hair on the spindles and a heater having passages to embrace the spindles and electrical resistance elements surrounding the passages.

16. In an apparatus for waving hair, a clamp, a pair of spindles mounted thereon, means for winding hair on the spindles, and a heater having passages to embrace the spindles and electrical resistance elements surrounding the passages, the passages being closed at one end to retain steam therein.

17. In an apparatus for waving hair, a clamp comprising opposed elements hingedly connected, means for securing the elements in closed position, one of the elements carrying a resilient jaw slidably supported therein and adapted to co-operate with the other element to clamp the hair.

18. In an apparatus for waving hair, a clamp comprising opposed elements hingedly connected, means for securing the elements in closed position, one of the elements carrying a resiliently mounted jaw adapted to co-operate with the other element to clamp the hair, the jaw having a projection to automatically divide the hair into two strands.

19. In an apparatus for waving hair, a clamp comprising opposed elements hingedly connected, means for securing the elements in closed position, one of the elements carrying a resiliently mounted jaw adapted to co-operate with the other element to clamp the hair, and a pair of spindles mounted on the clamp.

20. In an apparatus for waving hair, a clamp, a pair of spindles upon which contiguous strands of hair are adapted to be wound and means for securing the spindles on said clamp, said means being releasable to permit removal of the spindles for independently stripping the hair therefrom.

21. In an apparatus for waving hair, a clamp, a pair of spindles, means releasably securing said spindles on said clamp, means on the spindles for winding the hair helically thereon in reverse directions and means individual to each spindle and the corresponding connections between it and the clamp for preventing interchange of said spindles.

22. In a method of waving hair, the step of winding contiguous strands thereof helically in opposite directions.

23. In a method of waving hair, the steps

of clamping contiguous strands of the hair near the roots thereof and winding the strands helically in opposite directions.

In testimony whereof I affix my signature.
